Frank S. Palmeron
his ATTORNEY

UNITED STATES PATENT OFFICE.

VINCENT J. REDMOND, OF NEW YORK, N. Y.

ANTENNA.

Application filed March 5, 1926. Serial No. 92,460.

This invention relates to an antenna for wireless telephone or telegraph and has for an object to provide an improved construction wherein a large number of independent antennæ may be grouped together in a minimum space.

Another object of the invention is to provide an antenna structure wherein a large number of independent antennæ may be arranged on a comparatively small roof of a building and held in such a position as not to interfere with each other mechanically or magnetically.

A still further object of the invention is to provide an antenna structure wherein a number of supporting members are provided designed to hold independent antenna wires at different angles so as to prevent interference of the electrical impulses carried by the various wires.

In the accompanying drawings—

Figure 1 is a perspective view illustrating an embodiment of the invention as applied to a comparatively narrow building.

Figure 2 is an enlarged fragmentary perspective view showing one of the bracing members illustrated in Figure 1.

Figure 3 is an enlarged view in elevation of one of the wire supporting cross bars and associated parts.

Figure 4 is an enlarged view of the supporting foot embodying certain features of the invention.

Figure 5 is a cross-sectional view of Figure 4.

In this specification, the expression "antenna" is intended to be understood as a complete antenna construction including the wires, support and other means for use in telegraphic or telephonic communications for the reception or sending of messages. In the accompanying drawing, 1 indicates the roof of a building which is provided with fire walls 2 of usual construction which are really extensions of the walls of the building. Connected at suitable points to the fire walls 2 are clamps 3 which are substantially U-shaped members straddling the fire walls and secured thereto in any desired manner, as for instance, by expansion bolts 4. From each of the clamps 3 there is arranged a horizontal brace 5 and an inclined brace 6, said braces extending to suitable uprights 7. In the accompanying drawing there are shown five uprights 7 connected with clamps 3 though a greater or less number might be

used. In addition to the uprights 7 there are shown two uprights 8 connected to one set of uprights 7 by boards 9 and by bars 10 and 11. It will be noted that the uprights 8, together with their associated uprights 7, form an end framework while three uprights 7 form a second framework near the end of the building as illustrated in Figure 1.

For the purpose of clarifying the further description, one set of frames may be designated as frame 12 and the other as frame 13. The frame 12 is braced and connected to the fire wall 2 by five of the clamps 3 and associated parts while frame 13 is held 70 associated with the fire wall by two clamps 3. However, each of the uprights 7 is provided with a base 14 which is preferably formed of rubber in the form of a suction cup as shown in Figures 4 and 5 when these uprights are first placed in position, the bases 14 are collapsed in the usual manner so that a desired adhesion or suction will be produced. This assists the braces 5 and 6 and the clamps 3 in holding the respective frames 75 against accidental movement. Connected to frame 12 are cross bars 15, 16, 17 and 18, said cross bars being connected to the top bracing bars 11'. The frame 13 is provided with a similar set of cross bars 19, 20, 21 and 22 connected to the cross bar 11. If desired, additional cross bars could be mounted on the bars 10 and 10' but for the purpose of illustrating the invention the arrangement shown in Figure 1 illustrates how 90 the antenna wires are mounted so as not to interfere with each other. Each of the cross bars 15 to 22 inclusive, is provided with a pulley 23 at each end and each cross bar is preferably pivotally mounted in place by a 95 suitable pin 24 as shown in Figure 3. Passing through each of the pulleys 23 is a cord or rope 25 connected to an insulator 26 and to the opposite end of this insulator the respective wires are connected. As indicated in Figure 1, there are provided two wires for each set of cross bars, namely, wires 27, 28, 29, 30, 31, 32, 33 and 34. The various ropes or cables 25 are connected to the boards 9 and 9' respectively by suitable means, as 105 for instance, ordinary knobs 36 to which the cords are tied or fastened. In adjusting the various cords or ropes 25, they are made the proper length and so positioned as to simultaneously hold the wires taut and the various cross bars 15 to 22 at different angles whereby none of the wires 27 to 34 inclusive

will be parallel but, on the contrary, will be at different angles to each other and preferably also arranged so that the wires on any cross bar will be crossed.

- 6 In wireless or radio antennæ, it has been found that wires arranged parallel to each other and within certain distance of each other will interfere as the electrical influence from one will pass to the other. Therefore, 10 in a restricted area, as for instance, a comparatively narrow building, it is necessary to arrange the wires in some other manner than parallel if a large number are to be put on the roof as shown in Figure 1 and also 15 if there is to be no interference. By crossing the wires and by having the wires extend at different angles to the horizontal as well as vertical, the electrical impulse on one wire will not affect the electrical impulse on the 20 other as the point where an interference might be had is only at or adjacent the point of crossing which is, of course, spaced some distance apart. By arranging the various wires as shown in Figure 1 they are all at 25 an angle to the horizontal and at angles to each other even though the various cross bars are arranged on substantially parallel bars. If additional wires are used, care must be had to arrange them at different angles to 30 each other and to wires already in use. It is, of course, evident that the wires as shown may be readjusted to some other angle if additional wires necessitate such adjustment. The arrangement of the wires at the different 35 angles as described permits a large number of independent aerial wires to be used in a very restricted space and yet without interference.

What I claim is:

- 40 1. An antenna structure adapted to provide a comparatively large number of antenna wires in a minimum space, said structure including a pair of supporting frames, a plurality of pivotally mounted bars on each frame, a pair of wires for each two bars whereby the wires are arranged in pairs, and means for fastening said bars to the frames in such a manner that the wires of each pair will cross and all of the wires will be so arranged that no two will be parallel. 45 2. An antenna structure comprising a series of cross bars, a pair of wires for each pair of cross bars, a flexible member for each cross bar for holding the same in a given position, said position causing the wires of the cross bar to cross, and means for supporting the cross bars with a mini- 50 55

mum space therebetween in such a manner that the wires of one set of cross bars will not be parallel to the wires of any of the other cross bars. 60

65 3. An antenna structure comprising a pair of frames, a series of bars pivotally mounted on each of said frames, a pair of antenna wires for each pair of bars, said wires extending from the bars on one frame to the bars on the opposite frame, and a series of cords associated with each of said bars for holding the bars at different angles and thereby holding the various wires at different angles and out of parallelism. 70

75 4. An antenna structure comprising spaced supports, a spacing bar adjustably mounted on each support, spaced antenna wires connecting the spacing bars on opposite supports, said wires being insulated from each other, and means for adjusting the spacing bars relative to their supports for rendering the antenna wires non-parallel.

80 5. An antenna structure comprising spaced supports, a spacing bar pivotally mounted on each of said supports, antenna wires connecting the bars at spaced intervals and insulated from each other, and adjustable means between the pivoted bars and their supports for disposing the bars angularly with respect to their supports whereby to render the antenna wires non-parallel. 85

90 6. An antenna structure comprising spaced supports, a spacing bar pivotally mounted on each of said supports, antenna wires connecting the wires at spaced intervals and insulated from each other, and flexible means extending from the bars to the supports and having connection with said wires 95 for maintaining the wires taut and for maintaining the bars in adjusted angular position with respect to the supports whereby said wires are rendered non-parallel.

100 7. An antenna structure comprising spaced supports, a plurality of spacing bars pivotally mounted upon each of said supports, the several bars of each support being arranged in pairs, antenna wires connected at spaced intervals between the spacing bars 105 of each pair, the wires being insulated from each other, and means associated with the wires and bars of each pair for maintaining the said wires taut and the several bars at different angles with respect to the supports and to each other, whereby to render said wires non-parallel. 110
